Primary Examiner — Katie Jane Stofko*(74) Attorney, Agent, or Firm* — Banner & Witcoff, Ltd.(57) **CLAIM**

The ornamental design for a tablet, as shown and described.

DESCRIPTION

FIG. 1 is a front perspective view of a tablet showing our new design;

FIG. 2 is a rear perspective view thereof;

FIG. 3 is a bottom perspective view thereof;

FIG. 4 is a rear view thereof;

FIG. 5 is a front view thereof;

FIG. 6 is a right side view thereof;

FIG. 7 is a right side view thereof identifying features of FIG. 8;

FIG. 8 is an enlarged view of features shown in FIG. 7;

FIG. 9 is a left side view thereof;

FIG. 10 is a top view thereof; and,

FIG. 11 is a bottom view thereof.

The broken lines in the drawings illustrate portions of the tablet that form no part of the claimed design.
